(57) **CLAIM**

The ornamental design for an adaptor, as shown and described.

DESCRIPTION

FIG. 1 is a front, left side and top perspective view of an adaptor showing a first embodiment of our new design. FIG. 2 is a front elevational view thereof, the rear elevational view being a mirror image thereof. FIG. 3 is a left side elevational view thereof, the other side being a mirror image thereof. FIG. 4 is a front, right side and bottom perspective view thereof. FIG. 5 is a front, left side and top perspective view of the adaptor shown in FIG. 1 showing our new design in a different environment. FIG. 6 is a front elevational view thereof, the rear elevational view being a mirror image thereof. FIG. 7 is a left side elevational view thereof, the other side being a mirror image thereof. FIG. 8 is a front, right side and bottom perspective view thereof. FIG. 9 is a front, left side and top perspective view of an adaptor showing a second embodiment of our new design. FIG. 10 is a front elevational view thereof, the rear elevational view being a mirror image thereof. FIG. 11 is a left side elevational view thereof, the other side being a mirror image thereof. FIG. 12 is a front, right side and bottom perspective view thereof. FIG. 13 is a front, left side and top perspective view of the adaptor shown in FIG. 1 showing our new design in a different environment. FIG. 14 is a front elevational view thereof, the rear elevational view being a mirror image thereof. FIG. 15 is a left side elevational view thereof, the other side being a mirror image thereof; and, FIG. 16 is a front, right side and bottom perspective view thereof. The broken line showing of portions of the adaptor is for environmental purposes only and forms no part of the claimed design.
